DES. 2249

J. F. & J. Mix of Wallingford, County

Letters Patent No. 2249 Dated January 30, 1866

Design for a Spoon Handle

The schedule referred to in these Letters Patent and making part of the same

To all whom it may concern:

Be it known that J. F. & J. Mix of Wallingford, in the County of New Haven, and State of Connecticut, have invented a new and useful Design for a Spoon of Shanks, and I do hereby declare the following to be a full, clear and exact description of the same, reference being had to the annexed drawings making a part of this specification, in which,

Figures 1 and 2, are plan views of the upper and lower sides respectively of the spoon.

Figure 3, is a cross section of the shank.

To enable those skilled in the art to make my invention I will proceed to describe it with reference to the drawings.

The form of the bowl A, and handle B, may be the same as in ordinary spoons.

The central longitudinal portion of the shank C, is made convex in its cross section, the said convexity being formed upon the upper surface of the shank and narrowing to a point at that end which is next the handle B; its opposite end terminating more obtusely at the rear end of the bowl A. Extending laterally at each side of the convex part a, and along the whole length of the shank, is a flat rib m, upon the outer edge of which is an additional rib n. These ribs are turned down at an obtuse angle to the flat ribs m, as shown more plainly in Figure 3, and form the edges of the shank. The ribs m and n, extend the whole length of the shank, from the head B, to the bowl A.

Des. 2249

2

Spoons having their shanks formed with a central longitudinal convex part, with adjoining flat ribs on already turned such configuration I do not claim.

But what I claim as new and desire to secure by Letter Patent is

The design and configuration of the spoon shank, herein described and represented in the accompanying drawings
